(57) **CLAIM**

The ornamental design for a multi-tool with drum key, as shown and described.

DESCRIPTION

This application incorporates by reference in its entirety the design patent application filed on even date with the title Folding Tool With Drum Key, U.S. Application Ser. No. 29/674,613.

FIG. 1 is a top perspective view of the multi-tool in an expanded configuration;

FIG. 2 is a first side elevation view of the multi-tool in an expanded configuration;

FIG. 3 is a top perspective view of the multi-tool in a retracted configuration;

FIG. 4 is a first side elevation view of the multi-tool in a retracted configuration;

FIG. 5 is a second side elevation view of the multi-tool in a retracted configuration;

FIG. 6 is a bottom perspective view of the multi-tool in an expanded configuration;

FIG. 7 is a second side elevation view of the multi-tool in an expanded configuration;

FIG. 8 is a first end elevation view of the multi-tool in an expanded configuration;

FIG. 9 is a second end elevation view of the multi-tool in an expanded configuration;

FIG. 10 is a top plan view of the multi-tool in an expanded configuration;

FIG. 11 is a top perspective view of the multi-tool in a retracted configuration; and,

FIG. 12 is a bottom perspective view of the multi-tool in a retracted configuration.

All of the broken lines illustrate portions of the multi-tool that form no part of the claimed design.
